UNITED STATES PATENT OFFICE.

FRANK NOWAK, OF CHICAGO, ILLINOIS.

CLOTHES-WASHING APPLIANCE.

No. 920,987.

Specification of Letters Patent.

Patented May 11, 1909.

Application filed February 24, 1908. Serial No. 417,501.

To all whom it may concern:

Be it known that I, FRANK NOWAK, a citizen of the United States, residing at Chicago, in the county of Cook and State of Illinois, 5 have invented certain new and useful Improvements in Clothes-Washing Appliances, of which the following is a specification.

My invention relates to that class of clothes washing appliances comprising a handle, on the lower end of which is a device intended to clean the clothes by forcing water through the same when the handle is manipulated up and down. In addition, my improved construction has ribs or rubbers 10 on the bottom which contact with the clothes and rub the same when a rotary motion is imparted to the handle at the same time that the handle is pressed or forced down on the clothes. My improved appliance is so constructed 15 that during its operation on the clothes a liberal quantity of water is played or poured upon and forced through the clothes causing their thorough cleansing and also at the same time the rubbers assist in 20 the cleaning action.

On the accompanying drawing forming a part of this specification and to which reference should be made, I have illustrated a preferred and desirable embodiment of my 25 invention, and on this drawing—Figure 1 is a side elevation of the lower portion of my clothes washing appliance, the handle being broken away as is also a part or section of the outer conical casing; Fig. 2 is a view similar 30 to Fig. 1, and in its lower portion illustrates a central section through the internal structure of the device, and Fig. 3 is a bottom plan view of the washing appliance.

On the lower end of the handle 10, only a 35 portion of which is shown on the drawing, I attach a sheet metal, preferably zinc, conical, inclosing or housing casing 11, which at its upper end is supplied with a cylindrical socket 12 which receives the lower end of the 40 handle; the latter being held therein by a plurality of screws 13. As is clearly illustrated in the drawing, the lower circular edge or margin of the metallic cone 11 is bent upwardly to form a smooth bead or roll 14 for 45 the obvious purpose of not injuring the clothes during the washing or cleansing action of the device. The open bottom mouth of this cone is closed by a smaller sheet metal cone frustum 15 held in place somewhat 50 within the mouth of the outer cone 11 by

any suitable holding means, such as solder. At its center, this cone frustum closure has a depending cylindrical chamber or casing 16 open at its bottom end and closed at its upper end by a top wall 17. As is shown, the 55 lower margin or edge of this cylindrical casing or chamber is substantially at the same level as the bottom edge of the outer cone 11. A plurality, in the present instance three, of holes or openings 18 are provided in the internal cone frustum 15 and the top wall 17 is supplied with a corresponding number of smaller openings or holes 19. Connecting the corresponding apertures of the cone frustum 15 and the top wall of the central chamber or casing 16 I provide a plurality of tapered pipes 20 which are reversely bent, as clearly illustrated in Figs. 1 and 2. The 60 openings 18 are considerably larger than the apertures 19 so that when the device is 65 pressed down on the clothes and into the water in the tub containing the clothes this liquid is forced upwardly through the openings 18 into the pipes 20 and is discharged 70 through the latter and the ports or apertures 75 19 centrally on the top of the clothes. Since 80 the pipes 20 are tapered as described, the water issues from the mouths or apertures 19 at a much greater velocity than that at 85 which it enters the admission openings 18, the result being that the water is poured or 90 played on the clothes in such a manner as to effectively and efficiently remove the dirt 95 from the soiled clothes.

In the large lower mouth of the inclosing 90 cone 11, below the cone frustum 15 and disposed between the apertures 18, I provide a plurality of ribs or rubbers 21 which radiate from the external surface of the central chamber or casing 16 to the wall of the housing cone 11, the lower edges of these ribs or rubbers being substantially in the same plane as the lower margins or edges of the cone 11 and chamber 16. As is illustrated, these 95 ribs increase in width as they approach the bottom surface of the metal cone frustum 15 and therefore aid in directing the water to 100 the apertures 18.

The operation of this device is substantially as follows: Assuming that the soiled 105 or dirty clothes have been placed in a tub of the usual and ordinary construction with a liberal supply of soapy water, the clothes are acted upon by my improved washing appliance by an operator or manipulator press- 110

ing or forcing the same downwardly into the water and onto the clothes, at the same time turning the appliance in the hands so that the rubbers or ribs 21 during this rotary motion may rub the clothes and assist in the cleansing action. When the bottom of the cone 11 enters the water the latter, on continued downward movement of the appliance, passes into the tubes or pipes 20 and 10 issues through the discharge openings 19 with a considerably increased velocity and pours upon the top of the clothes also aiding in the cleaning of the clothes acted upon. Not only is this cleansing soapy water played 15 or poured upon the top of the clothes, but since the clothes have somewhat a tendency to float more or less in the water in the tub the water is also forced upwardly through the same when my washing appliance is 20 pressed down on the top of the clothes as described above. It is obvious therefore that by the combination of rubbing the clothes, forcing the water through the same and playing or pouring the water at a considerable 25 velocity on top of the clothes a thorough cleaning and cleansing action occurs.

Although I have described with some degree of particularity the exact structural features of my improved device, my invention 30 is not limited to the precise construction shown and described, and hence this may be varied within wide limits without departing from the heart and substance of my invention; for example, the exact shapes of the 35 various parts of my washing device are quite immaterial and the number of ribs or rubbers and pipes or tubes may be varied or modified as found desirable or necessary.

I claim:

40 1. In clothes washing appliances of the character described, the combination of a handle, a cone shaped inclosing casing fixed to the lower end of said handle, a closure for the open bottom mouth of said casing, and a 45 tapered, reversely bent pipe in said casing, having a liquid admission mouth at one end

through said closure, and at its other end a discharge mouth, substantially as described.

2. In clothes washing appliances of the character described, the combination of a 50 handle, a cone-shaped inclosing casing fixed to the lower end of said handle, a closure for the open bottom mouth of said casing, and a plurality of tapered reversely bent pipes in said casing each having a liquid admission 55 mouth at one end through said closure and at its other end a discharge mouth nearer the axis of the casing than its admission mouth, substantially as described.

3. In a clothes washing appliance of the 60 character described, the combination of a handle, a cone-shaped inclosing casing fixed to the lower end of said handle, a closure for the mouth of said casing in the form of a cone frustum, a chamber centrally located in said 65 cone frustum closure, and a plurality of reversely-bent tapered pipes with liquid admission mouths at one end through said closure, and smaller discharge mouths at their other ends through the top wall of said 70 central chamber, substantially as described.

4. In a clothes washing appliance of the character described, the combination of a handle, a cone-shaped inclosing casing fixed to the lower end of said handle, a closure for the mouth of said vessel in the form of a cone frustum, a chamber centrally located in said 75 cone frustum closure extended downwardly substantially to the lower margin of the said outer cone-shaped inclosing casing, a plurality of reversely-bent tapered pipes having liquid admission mouths at one end through 80 said closure, and smaller discharge mouths at the other end through the top wall of said central chamber, and a plurality of ribs below 85 said cone frustum closure and between the said central chamber and said outer inclosing casing, substantially as described.
